CLAIM

The ornamental design for a display screen with graphical user interface for athletic achievements, as shown and described.

DESCRIPTION

FIG. 1 is a front view of a display screen with graphical user interface for athletic achievements showing the new design; and,

FIG. 2 is a front view of a display screen with graphical user interface for athletic achievements of FIG. 1 shown on a device.

The broken line showing of the display screen in FIGS. 1-2, and the remainder of the device in FIG. 2 is for environmental purposes only and forms no part of the claimed design.
